FILTER-AND-THROTTLE UNIT FOR A SCROLL COMPRESSOR, AND SCROLL COMPRESSOR FOR A REFRIGERANT CIRCUIT

CROSS REFERENCE TO PRIOR APPLICATIONS

This application is a U.S. National Phase application under 35 U.S.C. § 371 of International Application No. PCT/EP2020/078292, filed on Oct. 8, 2020. The International Application was published in German on Apr. 14, 2022 as WO 2022/073611 A1 under PCT Article 21(2).

FIELD

The present invention relates to a filter and throttle unit for a scroll compressor, the filter and throttle unit comprising a housing with housing walls and an opening acting as a throttle or orifice, which is configured in one of the housing walls. The present invention also relates to a scroll compressor for a refrigerant circuit with a drive unit, an eccentric unit which can be driven by the drive unit and via which an orbiting displacement scroll can be moved, which engages in a stationary stator scroll, at least one displacement chamber between the stator scroll and the displacement scroll, and a high-pressure chamber into which the at least one displacement chamber opens, a low-pressure chamber which opens into the at least one displacement chamber, an oil return channel via which the high-pressure chamber is fluidically connected to the low-pressure chamber, a counterpressure chamber configured on the side of the displacement scroll facing away from the stator scroll, and a gas connection channel via which the counterpressure chamber is fluidically connected to the high-pressure chamber.

BACKGROUND

Such scroll compressors are in particular used for compressing refrigerants in refrigeration and air conditioning circuits of motor vehicles. The expanded refrigerant entering the scroll compressor is in a gaseous state and usually flows into the housing on the motor side, at least in the case of electric motor-driven scroll compressors, so that the refrigerant flows through the electric motor. The refrigerant also collects oil necessary for lubrication in the motor chamber, which is usually separated from the refrigerant in an oil separator on the scroll compressor and returned to the scroll compressor for lubrication. The compressed refrigerant returns to the refrigerant circuit via an outlet.

Such scroll compressors have previously been described, for example, in EP 3 404 264 A1 and comprise a high-pressure chamber, a low-pressure chamber, an orbiting displacement scroll, and a fixed stator scroll cooperating with the displacement scroll. The orbiting displacement scroll engages the stator scroll so that displacement chambers are defined between the displacement scroll and the stator scroll, in which the medium to be compressed is received and compressed. A counterpressure chamber is provided between the bearing housing of the compressor and the displacement scroll. The pressure prevailing in the counterpressure chamber and acting on the displacement scroll causes a resultant force in the axial direction, whereby the displacement scroll is pressed against the stationary scroll so that the scrolls are sealed with respect to each other.

A fluid connection between the high-pressure chamber and the counterpressure chamber via a gas connection

channel exists to create the contact pressure in the counter-pressure chamber, whereby the fluid under high pressure from the high-pressure chamber is also present in the counterpressure chamber. A gas connection throttle or orifice is arranged in the gas connection channel, the gas connection throttle or orifice controlling the mass flow of the fluid flowing into the counterpressure chamber and reducing the pressure.

The scroll compressor also comprises an oil return channel which fluidically connects the high-pressure chamber to the low pressure chamber. An oil intended for lubricating the components in the scroll compressor is separated from the compressed fluid via a separator which is arranged in the high-pressure chamber and which is returned to the low-pressure chamber via the oil return channel so that the returned oil can again be used to lubricate the components. An oil return throttle is arranged in the oil return channel to reduce the pressure of the returned oil.

A scroll compressor is also described in US 2005/0129556 A1 where a filter element is arranged in the oil return line in addition to the throttle in order to filter contaminants from the oil.

The disadvantage of the previously described scroll compressors is that either no filtering of the recirculated gas and oil takes place at all or that the effort to manufacture and install the filter element and the throttle is very high. A clogging of the filter elements in the return channels is also to be expected.

SUMMARY

An aspect of the present invention is to provide a filter and throttle unit that can be easily manufactured and installed in a scroll compressor with little effort. A further aspect of the present invention is to prevent a clogging of the filter elements in the scroll compressor.

In an embodiment, the present invention provides a filter and throttle unit for a scroll compressor. The filter and throttle unit includes a housing which comprises housing walls, an opening which is configured to act as a throttle, and a filter element which is arranged within the housing walls of the housing. The opening is arranged in one of the housing walls.

In an embodiment, the present invention also provides a scroll compressor for a refrigerant circuit. The scroll compressor includes a drive unit, a stationary stator scroll, an orbiting displacement scroll which is configured to be moved and to engage in the stationary stator scroll, an eccentric unit which is configured to be driven by the drive unit and via which the orbiting displacement scroll is movable, a high-pressure chamber, at least one displacement chamber which is arranged between the stationary stator scroll and the orbiting displacement scroll, a low-pressure chamber which is configured to open into the at least one displacement chamber, an oil return channel which is arranged to fluidically connect the high-pressure chamber to the low-pressure chamber, a counterpressure chamber which is arranged on a side of the orbiting displacement scroll which faces away from the stationary stator scroll, a gas connection channel which is arranged to fluidically connect the counterpressure chamber to the high-pressure chamber, and a filter and throttle unit. The at least one displacement chamber is configured to open into the high-pressure chamber. The filter and throttle unit is arranged in at least one of the gas connection channel and in the oil return channel.

BRIEF DESCRIPTION OF THE DRAWINGS

The present invention is described in greater detail below on the basis of embodiments and of the drawings in which:

FIG. 1 shows a perspective view of a throttle and filter unit according to the present invention;

FIG. 2 shows a side view of the filter and throttle unit according to the present invention from FIG. 1 in a sectional view; and

FIG. 3 shows a side view of a scroll compressor according to the present invention for a refrigerant circuit of a vehicle with a filter and throttle unit shown in FIGS. 1 and 2 in a sectional view.

DETAILED DESCRIPTION

The filter and throttle unit for a scroll compressor according to the present invention comprises a housing with housing walls which define an outer wall of the filter and throttle unit and thus delimit the unit axially and radially. An opening serving as a throttle or orifice is configured in one of these delimiting walls. A filter element is also arranged within the housing walls, and is thus also delimited at least radially by the housing walls. A unit consisting of throttle or orifice and filter element is accordingly provided which can simply be inserted as a whole into a corresponding receptacle on the scroll compressor. Assembly is thereby significantly simplified. Manufacturing is also simplified since the housing wall directly serves as a throttle or orifice through the configuration of the opening, so that no need exists to mount additional components therefor.

The scroll compressor according to the present invention comprises a drive unit, which can in particular be an electric motor. The drive unit drives an eccentric unit which is motion-coupled with a displacement scroll so that it performs an orbiting, i.e., an eccentric, rotational movement. The displacement scroll is usually arranged on a sliding disk and engages with a stationary stator scroll, which with the displacement scroll delimits one or more displacement chambers, which are reduced when the displacement scroll rotates along the stator scroll, so that a compression of the medium takes place in the circulating displacement chambers. The last displacement chamber opens into a high-pressure chamber into which the compressed medium flows, for example, via an outlet valve. The scroll compressor additionally comprises a low-pressure chamber which opens into the outer displacement chamber and which serves as an inlet, wherein the entire space in which the electric motor can be arranged also defines the low-pressure chamber. This is accordingly defined by the entire enclosed space of the scroll compressor, in which the fluid to be compressed is present in a relaxed state, in which it also flows into the scroll compressor. An oil return channel is also configured via which the high-pressure chamber is fluidically connected to the low-pressure chamber, wherein the fluidic connection is usually not direct, but via an oil separation chamber. The scroll compressor also comprises a counterpressure chamber which is configured on the side of the displacement scroll facing away from the stator spiral, wherein a gas connection channel fluidically connects the counterpressure chamber with the high-pressure chamber so as to generate a counterpressure via which the displacement scroll is loaded against the stator spiral. The present invention provides that the filter and throttle unit is arranged in the gas connection duct and/or in the oil return duct, which comprises a housing with housing walls delimiting the filter and throttle unit to the outside. An opening serving as a throttle or orifice is configured in one of these limiting walls of the filter and throttle unit. A filter element is also arranged within a space delimited by the housing walls. This configuration of a filter and throttle unit allows for an easy insertion of the unit

consisting of filter and throttle or orifice into a corresponding receiving opening in the scroll compressor in one assembly step. The unit can be attached by simply pressing it into place. The unit consisting of throttle or orifice and filter remains easily accessible and replaceable.

With regard to the filter and throttle unit, it is advantageous if the housing comprises an axially delimiting housing wall in which the opening serving as a throttle or orifice is configured, and an annular, radially delimiting housing wall which extends axially from the axially delimiting housing wall. A substantially pot-shaped component is accordingly provided, the housing of which does not require further assembly, but which can be manufactured in one piece.

In an embodiment of the present invention, the filter element can, for example, be configured in the form of a plate so as to delimit the filter and throttle unit on one axial side. This makes the filter element easily accessible and mountable in the housing. The plate-shaped design provides a surface of the filter element, especially for horizontally arranged compressors, which can be arranged perpendicular to the gravitational force so that a self-cleaning of the filter element takes place without external forces. The filtered-out solids do not thereby stick to the filter element even during the operation thereof.

In an embodiment of the present invention, the filter element can, for example, be configured as a filter screen which is radially delimited by a sealing element which is attached in the housing. The sealing element provides that no oil or gas can flow alongside the filter element. The screen comprises a sufficient filtering effect with high durability. The filter screen can also be easily attached to the housing via the sealing element.

In an embodiment of the present invention, the housing can, for example, be configured as a stamped part in which the filter element is attached in a form-locking manner with the sealing element. The design as a stamped part is just as cost-effective as the form-locking attachment of the filter element with the sealing element. This attachment can be produced, for example, by simply deforming the axial end of the annular housing wall.

In an embodiment of the present invention, the sealing element can, for example, rest with a first axial side against the axially delimiting housing wall and with its opposite axial side against an at least partially radially inwardly extending collar of the radially delimiting housing wall. The form-locking connection between the sealing element and the housing can thereby be established in a simple manner.

A tight connection is achieved when the sealing element is axially pressed between the collar and the axially delimiting housing wall, thereby providing that the gas or oil can flow exclusively via the filter element, which is surrounded by the seal.

The filter screen can, for example, be overmolded radially on the outside with a plastic of the sealing element so that the filter screen with the sealing element can be inserted as one part into the housing and attached thereto. This further facilitates assembly and manufacture. The filter screen can alternatively be inserted between two pressed sealing elements within the housing or attached between the collar and a sealing element.

In an embodiment of the scroll compressor according to the present invention, at least a section of the gas connection channel and/or the oil return channel can, for example, extend through the stator scroll. These channels can be easily incorporated during the manufacture of the scroll so that no additional machining is necessary.

In an embodiment of the present invention, the filter and throttle unit can, for example, be attached in the stator scroll. The filter and throttle unit can in particular simply be inserted into the corresponding channels before the stator scroll is mounted in the compressor housing.

It is particularly advantageous if the filter and throttle unit is pressed into an inlet opening on a cover disc of the stator scroll, wherein the filter element is configured in the form of a plate and delimits the high-pressure chamber. The filter element in this case extends to the same height as the wall surface of the cover disc of the stator scroll delimiting the high-pressure chamber so that a common wall surface is defined. There is thus no space in which the filtered-out contaminants can settle in front of the filter element. In the usual horizontal design of the compressor, these contaminants will instead always fall from the surface of the filter element back into the high-pressure chamber due to the gravitational force, thereby preventing a clogging of the filter element.

The gas connection channel can, for example, extend from the high-pressure chamber through the stator scroll and a bearing housing part to the counterpressure chamber. Few components must thereby be precisely aligned with each other during assembly so that the channel can be easily manufactured.

The high-pressure chamber can, for example, be connected with an oil separation chamber in which an oil separator is arranged. This allows the oil to be separated and returned to the low-pressure chamber so that the oil load on downstream components can be kept low.

The oil return channel can, for example, extend from a lowest point of the oil separation chamber through a head housing part, the stator scroll, and the bearing housing part, to the low-pressure chamber. Such a division and arrangement provides for a complete recirculation of the oil and allows for easy manufacturing and assembling.

The inlet opening of the gas connection channel can, for example, be arranged upstream of the oil separator in the direction of flow of the gas so that a gas-oil mixture enters the counterpressure chamber, and thus the bearing housing, thereby providing that the bearings and moving parts present there are sufficiently lubricated.

A filter and throttle unit and a scroll compressor for a refrigerant circuit of a vehicle is thus provided with such a filter and throttle unit which can be easily manufactured and assembled. Costs are thus reduced both in the manufacture of the filter and throttle unit as well as in their assembly on the compressor. A self-cleaning of the filter element is also achieved which also prevents clogging of the return channels.

An example of a filter and throttle unit according to the present invention as well as a scroll compressor according to the present invention are shown in the drawings and are described in greater detail below.

The filter and throttle unit **10** shown in FIGS. 1 and 2 comprises a housing **12** which consists of an axially delimiting housing wall **14**, which is configured to be slightly thinner in the radially inner region in the present embodiment, and an annular housing wall **16** which delimits the filter and throttle unit **10** radially and which extends axially from the radially outer edge of the axially delimiting housing wall **14**. This housing **12** can be produced particularly easily from sheet metal by punching and bending.

A narrow opening **18** serving as a throttle or orifice is configured in the inner thinner region of the axially delimiting housing wall **14**. Inside the annular radially delimiting housing wall **16**, an annular sealing element **20** is clamped

and axially pressed between the axially delimiting housing wall **14** and an axial end section of the annular radially delimiting housing wall **16** formed as a collar **22**, which is bent radially inwards. The first axial side of the sealing element **20** accordingly rests against the axially delimiting housing wall **14**, and the opposite axial side of the sealing element **20** rests against the collar **22**.

A filter element **24** which is configured as a filter screen is arranged on the open side of the housing **12**, which filter element **24** is configured in the form of a plate and whose radially outer edge is either overmolded by the plastic of the sealing element **20** or is clamped axially between two sealing elements **20** or between the collar **22** and the sealing element **20**. Oil or refrigerant can accordingly flow into the housing **12** via the filter element **24** so that solids are filtered out of the oil or refrigerant flow, and flow out of the filter and throttle unit **10** again via the opening **18** serving as a throttle or orifice, wherein the pressure downstream of the opening **18** is lower than the pressure upstream of the opening **18**. The mass flow is also significantly reduced by the cross-sectional constriction.

FIG. 3 shows a scroll compressor **26** according to the present invention which comprises a multi-part compressor housing **28** with a first motor housing part **30** and a head housing part **32** axially adjoining the first motor housing part **30**, wherein the first motor housing part **30** surrounds a drive unit **34** in the form of an electric motor, and the head housing part **32** surrounds a compressor chamber **36**.

The drive unit **34** comprises a stator **38** with windings **40** and an internal rotor **42** with permanent magnets **44**, which is attached to a shaft **46**. The shaft **46** and thus the rotor **42** are mounted on one side via a first ball bearing **48**, which is arranged in a receiving opening on an axially delimiting rear wall **50** of the first motor housing part **30**, and on the other side via a second ball bearing **52**, which is arranged in a receiving opening of a bearing housing part **54**, which is attached on the side axially opposite the rear wall **50** in the radial interior of the first motor housing part **30**. A shaft seal ring **56** is arranged in the bearing housing part **54** between the rotor **42** and the second ball bearing **52**, via which a motor chamber **58** in which the drive unit **34** is arranged is sealed with respect to a counterpressure chamber **60** which is configured on the axial side of the bearing housing part **54** opposite to the motor chamber **58**.

An electronics chamber **62** is configured on the opposite side of the rear wall **50** to the drive unit **34**, which drive unit **34** can be provided as an electric motor **34**, in which electronics chamber **62** a circuit board **64** with the power electronics **66** is attached. This is in turn connected to the windings **40** of the stator **38** so that it can be energized in a controlled manner. The power electronics **66** are supplied with power via a plug **68** which extends parallel to the motor axis from the rear wall **50**. The electronics chamber **62** is closed by a cover **70**.

An eccentric unit **72** is arranged on the end of the shaft **46** facing the compressor chamber **36**, on the output stud **74** of which an eccentric shaft bearing **76** is arranged, on which an orbiting displacement scroll **78** is eccentrically mounted, which corresponds with a stationary stator scroll **80**, which is attached in the head housing part **32** and to the bearing housing part **54**, so that, via an eccentric rotation of the orbiting displacement scroll **78**, the walls **82** thereof slide along the walls **84** of the stationary stator scroll **80** to form a plurality of displacement chambers **86**, thereby reducing the expansion of the displacement chambers **86** and thereby compressing the refrigerant drawn from a low pressure chamber **88**. The inlet from the low-pressure chamber **88**

into the displacement chambers **86** is configured radially between the head housing part **32** and the stationary stator scroll **80** so that the refrigerant is conveyed from the low-pressure chamber **88** radially inwards through the displacement chambers **86** towards an outlet **90**, which is configured on a cover disk **91** of the stationary stator scroll **80**, into a high-pressure chamber **92** via a non-return valve **94**, which is configured as a leaf spring element. The low-pressure chamber **88** is supplied with refrigerant via a (not visible) compressor inlet through which the refrigerant flows into the motor chamber **58**, which serves as the low-pressure chamber **88**.

A sliding disk **96** is arranged between the bearing housing part **54** and the stationary stator scroll **80** and the orbiting displacement scroll **78**, which is clamped in the radially outer region between the head housing part **32** and the first motor housing part **30**. This sliding disk **96** also comprises openings through which a plurality of pins (which are not visible in the drawings) protrude from the bearing housing part **54** into corresponding receptacles **98** of the orbiting displacement scroll **78**, on which sliding bushings **100** are arranged, via which the orbiting displacement scroll **78** is additionally slidably mounted. The orbiting displacement scroll **78** also comprises a sliding and sealing ring **104** which is arranged in a circumferential groove **102** on the side facing the sliding disk **96**. The orbiting displacement scroll **78** is accordingly arranged to slide with respect to the shaft **46** and the bearing housing part **54**.

The high-pressure chamber **92** of the scroll compressor **26** is fluidically connected to an oil separation chamber **106** in which an oil separator **108** in the form of a cyclone is arranged so that the lighter, gaseous refrigerant, flows to a compressor outlet **110** while the liquid, and heavier, oil in the cyclone is separated from the refrigerant and drips to a lowest point of the oil separation chamber **106** defined by a bottom **112**.

To discharge the oil deposited in the oil separation chamber **106**, the beginning of an oil return channel **114** is provided at the bottom **112** of the oil separation chamber **106**, which fluidically connects the oil separation chamber **106** and thus the high-pressure chamber **92** with the low pressure chamber **88** and the motor chamber **58**, respectively. The oil return channel **114** extends through the head housing part **32**, the stationary stator scroll **80**, the sliding disk **96**, and through the bearing housing part **54**, into the motor chamber **58**.

According to the present invention, the filter and throttle unit **10** is fitted, in particular pressed, into an inlet opening **116** of the oil return channel **114** at the cover disk **91** of the stationary stator scroll **80** so that the oil is returned to the motor chamber **58** with reduced pressure and filtered.

A gas communication channel **118** moreover extends from the high pressure chamber **92** through the stationary stator scroll **80**, the sliding disk **96**, and through the bearing housing part **54**, into the counterpressure chamber **60**, in which there is correspondingly a reduced pressure relative to the high pressure chamber **92** but an increased pressure relative to the low pressure chamber **88**, whereby the orbiting displacement scroll **78** is loaded against the stationary stator scroll **80**, resulting in an improved seal between the end faces of the orbiting displacement scroll **78** and the stationary stator scroll **80**.

In order to adjust this pressure, a filter and throttle unit **10** according to the present invention is also located at an inlet opening **120** into the gas connection channel **118** at the cover disk **91** of the stationary stator scroll **80**, the opening **18** of which is configured to correspond in size and which can be

pressed into the inlet opening **120**. The filter element **24** also prevents the penetration of contaminants into the counter-pressure chamber **60**, thus protecting the second ball bearings **52**, the eccentric shaft bearings **76**, the sliding bushings **100**, the sliding disk **96**, and the sliding and sealing ring **104** which are there arranged.

The filter surface of the filter element **24** is thus located approximately in one plane with the cover disk **91** of the stationary stator scroll **80** both at the inlet opening **120** of the gas connection channel **118** and at the inlet opening **116** of the oil return channel **114**. Dirt there filtered out thus does not settle in the oil return channel **114** or in the gas connection channel **118** to clog them, but falls into the high pressure chamber **92** due to gravitational force. Self-cleaning thus takes place. The functionality of the oil return channel **114** and the gas connection channel **118** is accordingly maintained over a long period of time. The filter and throttle units **10** can accordingly be easily removed and replaced, as they are easily accessible and easy to assemble and disassemble. Different desired back pressures can also be set by filter and throttle units **10** with different opening widths.

It should be clear that the scope of protection of the present invention is not limited to the described embodiment example, but that various modifications are conceivable. The scroll compressor can, for example, comprise any drive or the housing divisions can be changed. The filter and throttle unit can also be attached in the inlet openings in a different way as by press-fitting. Reference should also be had to the appended claims.

What is claimed is:

1. A filter and throttle unit for a scroll compressor, the filter and throttle unit comprising:
    - a housing which comprises housing walls;
    - an opening which is configured to act as a throttle, the opening being arranged in one of the housing walls;
    - a filter element which is arranged within the housing walls of the housing; and
    - a sealing element which is attached in the housing, wherein,
    - the filter element has a plate form and is configured to delimit the filter and throttle unit on one axial side thereof,
    - the housing walls of the housing comprise, an axially delimiting housing wall in which the opening is arranged, and
    - an annular radially delimiting housing wall which extends axially from the axially delimiting housing wall, and
  2. The filter and throttle unit as recited in claim 1, wherein,
    - the housing is provided as a stamped part, and the filter element is attached in a form-locking manner in the housing via the sealing element.
  3. The filter and throttle unit as recited in claim 2, wherein,
    - the annular radially delimiting housing wall comprises an at least partially radially inwardly extending collar, and the sealing element rests against the axially delimiting housing wall with a first axial side and rests against the at least partially radially inwardly extending collar of the annular radially delimiting housing wall with a second axial side which is opposite to the first axial side.
  4. The filter and throttle unit as recited in claim 3, wherein the sealing element is axially pressed between the at least partially radially inwardly extending collar and the annular radially delimiting housing wall.
- 10
5. The filter and throttle unit as recited in claim 1, wherein,
    - the sealing element comprises a plastic, and the filter element is overmolded radially on an outside with the plastic of the sealing element.
  6. A scroll compressor for a refrigerant circuit, the scroll compressor comprising:
    - a drive unit;
    - a stationary stator scroll;
    - an orbiting displacement scroll which is configured to be moved and to engage in the stationary stator scroll;
    - an eccentric unit which is configured to be driven by the drive unit and via which the orbiting displacement scroll is movable;
    - a high-pressure chamber;
    - at least one displacement chamber which is arranged between the stationary stator scroll and the orbiting displacement scroll, the at least one displacement chamber being configured to open into the high-pressure chamber;
    - a low-pressure chamber which is configured to open into the at least one displacement chamber;
    - an oil return channel which is arranged to fluidically connect the high-pressure chamber to the low-pressure chamber;
    - a counterpressure chamber which is arranged on a side of the orbiting displacement scroll which faces away from the stationary stator scroll;
    - a gas connection channel which is arranged to fluidically connect the counterpressure chamber to the high-pressure chamber; and
    - the filter and throttle unit as recited in claim 1, the filter and throttle unit being arranged in at least one of the gas connection channel and in the oil return channel.
  7. The scroll compressor as recited in claim 6, wherein at least one of,
    - a section of the gas connection channel extends through the stationary stator scroll, and
    - a section of the oil return channel extends through the stationary stator scroll.
  8. The scroll compressor as recited in claim 7, wherein the filter and throttle unit is fixed within the stationary stator scroll.
  9. The scroll compressor as recited in claim 8, wherein, the stationary stator scroll comprises a cover disk which comprises an inlet opening, the filter and throttle unit is pressed into the inlet opening on the cover disc of the stationary stator scroll, and the filter element has a plate form and is configured to delimit the high-pressure chamber.
  10. The scroll compressor as recited in claim 6, further comprising:
    - a bearing housing part, wherein,
    - the gas connection channel is arranged to extend from the high-pressure chamber through the stationary stator scroll and the bearing housing part to the counterpressure chamber.
  11. The scroll compressor as recited in claim 10, further comprising:
    - an oil separation chamber having an oil separator arranged therein, wherein,
    - the high-pressure chamber is connected with the oil separation chamber.

12. The scroll compressor as recited in claim 11, further comprising:
a head housing part,
wherein,
the oil return channel is further arranged to extend from 5
a lowest point of the oil separation chamber through the
head housing part, the stationary stator scroll, and the
bearing housing part, to the low-pressure chamber.
13. The scroll compressor as recited in claim 11, wherein,
the gas connection channel comprises an inlet opening 10
which is arranged upstream of the oil separator in a
direction of flow of a gas.
